UNITED STATES PATENT OFFICE

ANTHONY PAUL MILLER, OF PLEASANTVILLE, NEW JERSEY

METHOD OF INSTALLING SHEET PILING

Application filed June 15, 1931. Serial No. 544,444.

The present invention is concerned with a method of installing sheet piling and considered from one aspect is capable of a wide and varied range of utility in connection with sheet piling installations regardless of the purpose for which the piling is to be used.

Considered from another aspect, however, the invention is generically concerned with the provision of a method of sheet piling installation which will obviate the need for shoring or under-pinning a building during the process of digging an excavation adjacent thereto.

In other words, while the method of piling installation completely obviates the present undesirable methods of jetting or driving the sheet piling, it is unique in that it is the only method thus far devised for effectively eliminating the need for under-pinning or shoring where an excavation is to be made as deep or deeper than the footings of adjacent standing structures.

Driving methods of installing sheet pilings create vibration waves which spread to adjoining foundations, causing settlement, cracking or crumbling of these foundations. Also, the noise attending such percussive means of installing sheet pilings is quite annoying.

Water jetting methods of installing any type of pilings are frequently disadvantageous inasmuch as they cause settlement of the surrounding soil, and thereby endanger the foundations of surrounding structures.

Such methods also entail the use of pumping units for creating high pressure jets, and the splashing and splattering of the water attending such a method causes a messy condition around the construction region.

An object of the present invention therefore is to provide a method by which sheet pilings may be installed in a simple and inexpensive manner without the use of either driving or jetting apparatus which might subject the soil to excessive vibrations, or cause undesirable settlement thereof.

Another object is to provide a method of installing foundations closely adjacent a previously erected building wherein sheet piling is used and each section of piling is

pretested as it is installed, the pretesting being sufficient to determine whether or not the individual sheet piling sections are capable of sustaining their share of the load which will be eventually transmitted to them through the soil by the adjacent structure.

Another object of the invention is to provide a method of piling installation wherein the possibility of displacement or caving in of the pretested sheet piling is further guarded against by the use of supplemental bracing members which are applied at intervals as the excavation proceeds. These supplemental bracing members may be and theoretically are merely an added safety factor, but by utilizing them the span of the sheet piling in which flexing may occur is considerably minimized.

In carrying out my invention, I sink shafts one at a time in the soil along the boundary line of the proposed excavation as by the use of conventional post hole augers. The sheet pilings which are a width corresponding approximately to the diameters of the shafts or holes are then dropped into the holes with their lower ends embedded in the soil to afford a toe-hold. The top portions of the edge keyed pilings are then braced against lateral movement by the use of a waler, or the like, and the cavities defined by the outside surfaces of the pilings and the corresponding outer walls of the shafts are filled in with part of the previously removed soil or other suitable material. This filler material is tamped or otherwise compacted, so that it will exert a lateral pressure on said sheet piling toward the area to be excavated so that these pilings will be stressed sufficiently to counteract the effect of pressure exerted by surrounding structures.

After the sheet pilings have been so installed and pretested, the excavation can then be started, the intermediate portions of the sheet piling being further braced against undue inward flexing as the excavation proceeds. In other words, having installed and pretested the sheet piling as to its load carrying ability, and having thus ascertained the fact that the sheet piling will sustain the load, even when flexed throughout the entire

length of its span between a waler at the surface of the ground and the bottom embedded portion thereof, an added safety factor is provided by the installation of lateral 5 bracing members emplaced as the excavation proceeds, these bracing members serving to subdivide the maximum flexed span of the piling into a plurality of smaller spans which can even more effectively sustain the load of 10 the adjacent structures. Preferably the nature of the bracing structure is such that it would sustain the loads transmitted laterally and downwardly through the soil, even though the sheet piling was unkeyed, and 15 even though it had no toe-hold.

This method of eliminating shoring and underpinning, while capable of use in any type of soil, is peculiarly adapted for use in water-bearing sand, such for instance, as 20 beach sand, since the pretesting of the piling is materially expedited due to the facility with which the sand may be packed in behind the pilings and tamped for pretesting purposes. Furthermore, the installation of a 25 foundation in water-bearing sand where conventional well points are used to dewater the sand at the excavation site, is conducive to an actual flow of sand under a subadjacent structure toward the excavation. In the 30 present instance, the sheet piling, while permitting the free flow of water toward the well points from which it was pumped to dry the soil, acts as a positive preventative of the flow of sand with the water.

35 In the accompanying drawings, there is shown for the purpose of illustration, one specific form by which the present invention may be carried out. In these drawings

40 Fig. 1 is a diagrammatic top plan view of the proposed excavation region adjacent a standing structure.

Fig. 2 is a section taken on the line 2—2 of Fig. 1, and showing the lines of force radiating from the foot of structures adjoining the 45 excavation.

Fig. 3 is a view partly in elevation and partly in section, and showing the first step in the method, i. e. the sinking of a shaft by use of a post hole digger.

50 Fig. 4 is a section which shows the next step of emplacing a waler and dropping a section of the sheet piling in position.

Fig. 5 is a section transverse to that shown in Fig. 4, and showing the soil packed in behind the piling section to pretest the latter.

Fig. 6 is a vertical section through an area in which the excavation has already been accomplished, and

60 Fig. 7 is a section taken on line 7—7 of Fig. 6, and showing the process of concreting the wall of the completed excavation.

In Figs. 1 and 2, I have shown the area A representing the area of the proposed excavation, this area being adjacent a heavy 65 standing structure, such as the building B.

The weight of the building B is distributed through the soil as a force acting approximately in the directions indicated by the lines C, it being understood that the particular angle of load distribution through the soil will be determined to a large extent by the 70 nature of the soil itself. The forces acting through the vertical plane indicated by the heavy line D, which represents that proposed wall of the proposed excavation nearest the building B, would tend to cause the soil under the footing of the building B to move laterally into the excavated area when the reactionary forces exerted by the soil itself, are destroyed by the process of excavation. 75 Consequently some means must be provided either to support the footing of the building A during the period of excavation, or some other means must be provided for effectively counteracting the forces indicated by the 80 lines C and thereby preventing inflow of soil into the excavation and settlement or collapse of the building.

Prior to the present invention, it has been customary either to underpin the building 85 where the excavation was to be made considerably deeper than the footings of the standing structure, or to support the building by shoring or equivalent bracing means.

Insofar as I am aware, the use of sheet pilings to line the walls of the proposed excavation for the purposes of preventing undermining or settlement of an adjacent structure, has not heretofore been satisfactory or safe, 90 principally because there was no method of safely utilizing such pilings with any assurance that they would prevent collapse of the excavation or settlement of the building. Furthermore, the methods which have been previously used for installing sheet piling 95 were in themselves not of a character which would permit piling to be safely used in lieu of underpinning or shoring. That is to say, the use of percussive means or of jetting means, might create disturbances in the soil 100 under the standing structure and cause settlement thereof before excavation work was ever started. Furthermore, by prior methods of sheet piling installation, the engineers in charge of excavation, have not been able 105 to assure themselves that the sheet piling would carry the lateral load imposed upon it since there has heretofore been no method of pretesting the ability of the piling to carry the load.

In accordance with the present invention, prior to digging the excavation, I form a retaining wall of sheet piling along the line D in order to guard against settlement of the structure B, each individual piling being pretested as an incident of its installation so 115 that the ability of the piling to carry the load has been proven before any actual excavation work is started.

In accordance with the method, the first 120

step is to drill a shaft such as E with its center on the line D which is the side line of the proposed excavation. This shaft may be formed with an ordinary post hole digger or 5 auger F, or by any other convenient means, the diameter of the shaft being substantially equal to the width of the sheet piling section to be installed.

The depth of this shaft would depend on 10 the desired depth to which the excavation is to be made, but should preferably extend below the bottom of the excavation, since the bottom of this shaft would have a layer of loose soil collected thereat as the result of 15 the falling or flow of this soil during the boring process and pile installation. Also, by forming a shaft E which extends below the bottom of the excavation, the lower portion of the sheet piling subsequently installed 20 therein will have the lower end thereof firmly held and embedded below said bottom of the excavation, so that when the excavation is accomplished, the lower end of the sheet piling will still be retained in firm, anchored 25 position. A small amount of soil may be dumped in and tamped if desired, to form the toe hold.

After the shaft E has been formed in the soil, a sheet piling G is lowered therein. Although 30 this sheet piling may be of wood or concrete, it is preferable, for the purpose of the present invention, that it be made of steel, and may be of the usual form having means along the edges thereof for interlocking it 35 with or keying it to adjacent sections. The sheet piling G is disposed in the shaft E in substantially vertical position and the lower end thereof embedded in the soil at the base of said shaft. Since the soil at the bottom 40 of the shaft E includes loose soil which has fallen or flowed therein during the formation of said shaft or fallen during placing of pile, the lower end of the sheet pilings G will be very easily embedded in this loose soil. 45 If desired, pressure may be applied to the upper end of the sheet piling to embed the lower end of the piling in the firm compact ground.

Furthermore, the momentum and weight 50 of the steel piling as it is dropped into the excavation, causes the foot of the piling to embed itself in the soil, usually to a sufficient extent to form an effective toe-hold. It will be understood that the weight of the building 55 will be ineffective to cause collapse of the walls of the shaft E due to the fact that the soil which encircles this shaft has a true arch effect and efficiently carries the weight of the building.

60 A number of these sheet pilings E may be similarly installed by boring a corresponding number of shafts sufficiently close to each other to permit interengagement of the longitudinal edges of adjoining sheet pilings disposed therein. After a number of such sheet

pilings have been installed, the upper ends thereof may be maintained in aligned anchored position, and braced against inward deflection towards the excavation region A by a suitable bracing member such as a wale 70 piece H.

After the sheet pilings G have been so installed, the spaces J defined by the outer faces of said sheet pilings and the corresponding walls of the shafts E, are filled with packing material. Although these spaces J may be filled before the upper ends of the pilings are braced and anchored in position, it is preferable that both ends of the pilings be anchored in position before the filling operation 75 is begun. The filler material may consist of soil previously taken from the boring of the shaft E, or if desired, a dry mixture of concrete may be substituted. This filling material in the spaces J is then packed very firmly 80 in order to stress the sheet pilings sufficiently for them to exert reactionary forces which balance the forces created by the structure B. For that purpose, the filling material 85 may be packed by means of a standard tamping tool, a piece of lumber, by the puddling of water, or by other similar means. The stress exerted by the packing of this filling material in the spaces J will cause slight deflections of the pilings, the span of the deflection being determined by the distance between the wale piece H and the toe hold of the piling in the soil, shown somewhat exaggerated in Fig. 5.

If desired, as each shaft is bored and the piling G disposed in place, the space J associated therewith may be filled and the material packed before boring an adjoining shaft. In any event, too many of these shafts should not be bored and left unprotected at the same time, for a plurality of unprotected shafts, particularly adjoining shafts, might permit movement of the soil under the pressure action of the adjoining structures.

After the sheet pilings G have been installed in position as shown in Fig. 5, the excavation of the area A may then be started. It should be noted that during the process of installing the pilings as shown in Fig. 5, some of the soil will probably have flowed or fallen into adjoining relationship with the inside surface of these sheet piles. Under these conditions, this soil would tend to react against the forces created by the structure B, and serve, therefore, to decrease the degree of deflection of the sheet pilings G. The absence of the reactionary forces caused by the removal of this material during excavation, may subject these sheet pilings to greater resultant stress from the pressure exerted by the structure B, and also have a tendency to throw these pilings out of alignment. It may therefore, be desirable as the excavation proceeds downwardly, and as the material is removed from contact with the in-

side surfaces of said pilings, to compensate for such removal by bracing the intermediate portion of these pilings. For that purpose, the inside surfaces of the sheet pilings are braced by wale pieces K or other suitable bracing members disposed adjoining the inside surfaces of the sheet pilings G, and urged into engagement with these sheet pilings surfaces by means of timber bracing members L as shown in Figs. 7 and 6.

The ability of the wale pieces K to effectively sustain the piling against further buckling, may also be pretested by driving wedge members M between the walers and the inside surface of the sheet pilings.

As the excavation proceeds downwardly and additional wale pieces and bracing members are employed, the span of deflection of the pilings is reduced. That is to say, during the original pretesting of the piling, the latter was free to flex throughout the entire span between the surface waler and the toe hold, whereas the addition of other wale pieces during the process of excavation gradually cuts down this large deflection span and subdivides it into a plurality of smaller spans, adding a further safety factor.

After the excavation of the region A has been accomplished, it may be desired to line the excavated region with concrete as is customary in the building of foundations. For that purpose, the sheet pilings may be retained in position, and a concrete wall formed adjacent the inside surfaces of these pilings.

In Fig. 7, is shown the excavated region A in the process of being lined with a concrete foundation. The concrete foundation wall N is shown constructed adjacent the lower portions of the sheet pilings. After this wall has been formed to a height close to the lower bracing members, L and M, and has been hardened sufficiently to sustain the sheet pilings against the inward pressure exerted by the soil on the outer surfaces of said pilings, these lower bracing members may then be removed, the wall N, under these conditions, compensating for the removal of these lower bracing members. After these lower bracing members have been removed, the building of the wall N upwardly, is continued until the next bracing member is reached. The new addition to the concrete wall N is then permitted to harden, and the next bracing members right above it removed. This process is continued until the desired concrete foundation wall on the sides of the excavated region, has been formed. In this manner, the pilings G are retained in braced position, during the laying of the foundation wall, and the soil outside the excavated area supported against settlement.

It should be noted that by means of my improved method, the installation of sheet pilings is accomplished without endangering

the foundations of adjoining structures. Also the method is simple and inexpensive, and does not create the messy and noisy conditions incidental to the installation of pilings by present methods.

From the foregoing description, it will be apparent that the method is peculiarly effective for eliminating under-pinning and shoring when making a foundation near a standing structure. Entirely aside from such use, however, the method of piling installing herein described, may be carried out for open trench work in the fields, and in locations where the problem of lateral displacement of the soil is slight, since the method in any event, eliminates the need for the cumbersome, expensive apparatus which is usually difficult to transport into out-of-the-way localities.

The invention is susceptible of use in connection with various types of soil, but it has certain unique advantages when utilized in beach sand, particularly water-bearing sand which has been dewatered and which is substantially incompressible and flows freely if rewatered. Among these advantages are the facts that driving of any type of piling in such sand is extremely difficult and that the sand is a particularly effective medium for packing and pretesting the piling and the tamping of this material, which may be simply accomplished by pouring water thereon.

I claim:

1. The method of installing sheet pilings along a proposed line of excavation, which includes the steps of forming substantially vertical shafts along said line of excavation, disposing the sheet pilings in said shafts, and disposing a filler in the cavities formed between the outer surfaces of said sheet pilings, and the corresponding outer walls of said shafts.

2. The method of installing sheet pilings along a proposed line of excavation, which includes the steps of drilling substantially vertical shafts along said line of excavation, said shafts extending to a depth below the bottom of the proposed excavation, disposing the sheet pilings in said shafts, and disposing a filler in the cavities formed between the outer surfaces of said sheet pilings, and the corresponding outer walls of said shafts.

3. A method of installing sheet pilings along a proposed line of excavation, which includes the steps of forming shafts along the proposed line of excavation, disposing the sheet pilings in said shafts in substantially vertical position, disposing a filler in the cavities formed between the outer surfaces of said sheet pilings, and the corresponding outer walls of said shafts, and packing said filler so that said filler exerts a lateral force on said sheet pilings sufficient for said pilings to exert reactionary forces which bal-

ance the forces created by adjoining structures.

4. The method for installing sheet pilings along a proposed line of excavation, which includes the steps of forming along said line of excavation shafts, extending to a depth below the bottom of the proposed excavation, disposing the sheet pilings in said shafts, and anchoring the ends thereof in substantially vertical position with the lower ends thereof extending below the bottom plane of excavation, disposing a filler in the cavities between the outer surfaces of said sheet pilings, and the corresponding outer walls of said shafts, and packing said filler, so that it exerts a lateral force on said sheet pilings.

5. The method for installing sheet pilings along a proposed line of excavation, which includes the steps of forming substantially vertical shafts along the proposed line of excavation, disposing the sheet pilings in said shafts, filling the cavities formed between the outer surfaces of said sheet pilings, and the corresponding outer walls of said shafts with loose material, and bracing the upper ends of said sheet pilings to prevent these upper ends from moving out of alignment, and from deflecting inwardly towards the proposed region of excavation.

6. The method for installing sheet pilings along a proposed line of excavation, which includes the steps of drilling shafts substantially vertical along said line of excavation, disposing the sheet pilings in said shafts, disposing a filler in the cavities formed between the outer surfaces of said sheet pilings, and the corresponding outer walls of said shafts, and excavating and bracing the intermediate sections of said sheet pilings at intervals against undue inward flexing as the excavation uncovers said intermediate sections.

7. The method for installing sheet pilings along a proposed line of excavation, which includes the steps of drilling shafts substantially vertical into the soil, disposing the sheet pilings in said shafts, and disposing the material recovered from said shafts into the cavities formed between the outer surfaces of said sheet pilings and the corresponding outer walls of said shafts.

8. The method of constructing a foundation, which includes the steps of drilling shafts into the soil along the proposed line of excavation, disposing sheet pilings in said shafts with the bottoms thereof embedded in the soil, disposing a filler in the cavities formed between the outer surfaces of the sheet pilings, and the corresponding outer walls of the shafts, anchoring the ends of said sheet pilings in position, excavating and reinforcing the intermediate portions of the sheet pilings by bracing members as the excavation proceeds, building a concrete foundation wall in sections adjacent the sheet

pilings, and removing the bracing members associated with said pilings, each concrete wall section extending vertically between adjacent reinforced portions of said pilings, and being built and hardened successively, said bracing members being removed only when the adjacent concrete wall section just below them have hardened sufficiently to structurally compensate for the removal of these bracing members.

Signed at Pleasantville, in the county of Atlantic and State of New Jersey, this 11th day of June A. D. 1931.

ANTHONY PAUL MILLER.
